UNITED STATES PATENT OFFICE.

DAVID E. WHITON AND LUCIUS E. WHITON, OF NEW LONDON,
CONNECTICUT.

DRILLING-MACHINE.

SPECIFICATION forming part of Letters Patent No. 426,347, dated April 22, 1890.

Application filed February 4, 1889. Serial No. 298,677. (No model.)

To all whom it may concern:

Be it known that we, DAVID E. WHITON and LUCIUS E. WHITON, citizens of the United States, residing at New London, in the county 5 of New London and State of Connecticut, have invented certain new and useful Improvements in Center Drilling-Machines, of which the following is a specification.

Our invention relates to that class of machines in which rods or other work are prepared for turning, and which are commonly provided with a laterally-movable head having two spindles, one of which carries a drill and the other a reamer; but many of its details may also be advantageously applied to ordinary drilling-machines having two or more spindles.

Our invention has for its object the simplification of construction and the promotion 20 of accuracy and convenience in the performance of such work.

In the drawings accompanying and forming part of this specification, Figure I is a plan view of a machine embodying our improvements with a portion of the cap removed, and showing one of the spindles. Fig. II is a sectional elevation of the front or working side. Fig. III is a plan view of the intermediate or base piece which carries the swinging head. Fig. IV is a side elevation of a modified form of the laterally-moving head. Fig. V is a cross-section of the head on line *m n* of Fig. II, it being assumed that one spindle is moved forward for the performance of 35 its work. Fig. VI is a plan view of the under side of the laterally-swinging head, the spindles and gear-racks being removed. Fig. VII is an end elevation of the adjustable rest, work, and a portion of the bed, taken from the left of the machine. Fig. VIII is an end elevation of the vise, taken from its right, showing the oiling device and stop for the work. Fig. IX is a view of the supplemental opposing and supporting jaws of the vise. 45 Fig. X is a detail view on line *z z* of Fig. II.

Similar characters are used to indicate like parts in all the drawings.

The working parts may be mounted upon a frame or bed of any convenient construction, 50 supported upon legs or otherwise, such a bed being designated throughout the drawings by

A. Said bed may be directly provided with pivot-journals *B'*, Figs. II and III, for pivotally supporting a laterally-swinging head, or with guideways *A' A'*, Fig. IV, extending 55 transversely across the bed to support and guide a laterally-sliding head, or instead of the bed having formed directly thereon supports for the head, as the pivots *B³* and bearings *B'* or guideways *A'*, it may be provided with 60 an intermediate piece *B*, provided with such pivot-journals or crossways at option. We prefer to use the intermediate piece in the case of the swinging head, because interchangeable construction may be effected 65 thereby with less cumbersome fixtures or jigs. A swinging head *C*, carrying spindles, is pivoted in these journals *B'* and is free to swing laterally in either direction far enough to bring each of its spindles successively to an operative 70 position on the same line, the machine being so organized that this line is a prolongation of the center line of the work, and indicated by *x y*, Figs. I and II. Said swinging head is provided at one end with bearings *C'*, 75 within which spindles *D* are free to revolve and slide endwise, and at the other end with bearings *C²*, of larger diameter, in which journals *E²* of pinions *E* may revolve. It has a single cap *C³* for these bearings to permit the insertion of the spindles. Said cap has a convenient handle *C⁴*, by which the head may be moved laterally. These journals *E²* of the pinions *E* are hollow and are prevented from 80 endwise motion by shoulders *E'*, Fig. II. They 85 are mounted around the spindles *D*, and serve to transmit rotary motion to said spindles by means of keys *z*, Fig. X, and keyways in the ordinary manner of such constructions, leaving said spindles free to move endwise independently of their rotary motion. Between bearings *C'* and *C²* the swinging head is chambered or bored out to a diameter larger than 90 said bearings to permit end motion of collars *D'*, with which spindles *D* are provided, and 95 to receive sliders *F*, which communicate end motion to said spindles. These chambers *C⁵* of swinging head are made enough longer than that portion of the spindles between the outsides of collars *D'* to permit the required 100 amount of end movement in the spindles. The advance of the spindles will thus be lim-

ited by the abutment of the collars D' against the shoulders C⁶. Between these shoulders and the bearings C' a further chamber C⁷ is provided of smaller diameter than chamber 5 C⁵, within which spiral springs D², mounted around the spindles in a manner tending normally to hold said spindles in their withdrawn position, may be compressed by the forced advance of the spindles. In the bottoms of 10 the chambers C⁵ slots C⁸, Figs. II and IV, are made, through which sliders F, having sections of rack-teeth F', protrude. It will be seen that said sections of rack may consist of but one or more teeth, at option. These sliders 15 are so mounted in said chambers as to be in contact with the collars D', Fig. II, of the spindles and are free to move endwise, but are prevented from turning with the spindles by their engagement with the slots C⁸, Fig. V. It will be seen that any endwise motion which 20 they may receive will be transmitted to their respective spindles through their contact with the collars D'. In order that said sliders may receive endwise motion, a pinion G is pivoted 25 at such distance below the swinging head in the intermediate piece B or bed A, at option, that its teeth may become successively engaged with the teeth of the various sliders F, only one of which is shown in Fig. V. This 30 pinion G is without lateral movement, being pivoted in the slot B² of the fixed base B, but is capable of rotary movement by means of the hand-wheel H or otherwise. In case the head is supported by the first-described 35 method—that is, the pivots B³ and journals B', whereby it has pivotal swinging movement—the teeth of the pinion G may be curved with a radius corresponding to the distance of the rack-teeth of the sliders F from 40 the pivot-line of the swinging head, or in case the head is arranged to slide laterally on the ways A', Fig. IV, they may be left straight. Thus in either case their contour may be made to correspond with the lateral path 45 through which said rack-teeth F' move.

In order that the laterally-moving head may be held in the required position during the successive operation of its various spindles, and in order to prevent all lateral movement of the head except at times when the 50 operating-spindle is wholly withdrawn from its work, the feeding-pinion G is made in a mutilated or segmental form, as shown, and is so placed with reference to the rack-teeth 55 of the sliders F that its front radial surface G' may stand in an approximately vertical position when the spindles are so withdrawn. The under side of the laterally-moving head is provided with projecting lugs C⁹, of such 60 length as to permit the lateral movement of the head in front of the segmental pinion G when its forward radial surface is in a vertical position, but to preclude such lateral movement at times when said pinion and 65 connecting-spindle are advanced. Between said lugs C⁹ are slots C¹⁰, which are extensions of slots C⁸ carrying the sliders F, into

which slots the pinion G may advance in certain positions, such positions being so located as to bring the corresponding spindles to 70 their operative position. Assuming that the width of these slots C¹⁰ corresponds to the thickness of the pinion G, it will be seen that said pinion and its connecting-spindle can only be advanced when in an operative position; also, assuming that said pinion and spindle are advanced, it will be seen that no lateral movement of the head can occur. In order that the spindles D may receive rotary motion through their pinions E, one of the 75 pivots B³ upon which the head swings is extended and forms a journal. A pulley I, carrying pinions I' of proper size to mesh with the pinions E, is caused to revolve upon this journal by means of a belt. Power is thus 80 transmitted to the spindles in any position which they may occupy. It is obvious that friction-disks or any analogous device may be employed in place of the pinions E and I' within the scope of our invention. For 85 the convenient indication to the workman that the head has received sufficient lateral movement stops J are provided, against which the head may be moved by means of handle C⁴, said stops being adjusted to correspond with the proper position of the slots 90 C¹⁰ underneath the head.

For the purpose of gripping the work a vise is mounted upon the bed, and for convenience is capable of longitudinal movement thereon and may be clamped at any desired point. This vise has opposing gripping-jaws K K', sliding on ways L L', which approach or recede from each other by the action of a right-and-left screw in the ordinary manner. Said vise has also supplemental opposing jaws K² K³, moving simultaneously with said gripping-jaws, which serve as a V-shaped rest or support for the work, and which in closing automatically lift 105 the work to a central position, corresponding to the position in which the work will be held by the gripping-jaws. A supporting-rest is provided at the left of the vise, which is also capable of longitudinal movement and clamping 110 at any convenient point upon the bed of the machine. Said rest is provided with opposing supporting-jaws M M', moved by a right-and-left screw in the same manner as the jaws of the vise, and mechanically resembles 115 the vise in all respects, except that it is without gripping-jaws, having only supporting-jaws tending to lift the work in the same manner as the supplemental jaws K² K³ of the vise. The actuating-screws of the vise and rest being connected by gears N and shaft N', as 120 shown, it is clear that automatically-adjusting V-shaped supports for each end of the work are provided by the opposing jaws M M' of the rest and the supplemental jaws K² K³ 125 of the vise. The shaft to be centered is therefore simply laid in the two V-shaped supports, and there remains no necessity for the operator to support the weight of the work 130

while adjusting it in the gripping-jaws, which in work of the heavier class is a matter of much inconvenience. The work being thus supported in the rests, it is moved forward

5 through the gripping-jaws of the vise, which are then clamped upon it and the drilling may be performed.

In the performance of work of this class it is of frequent importance that the reaming

10 be not carried to too great a depth, as this unnecessarily enlarges the diameter of the recess in the end of the finished piece and injures the neatness of its appearance. It is also of frequent importance that many pieces

15 be reamed to the same depth, and in all cases the cutting-tools require to be supplied with oil or other lubrication in order to the best performance of their work. These results are achieved in our machine as follows: It being

20 previously understood that the advance of the drilling-spindles D is limited by the abutment of collars D' against shoulders C⁶, it is clear that the advance of the cutting-tools carried by said spindles is also thus limited.

25 A cross-bar or stop-plate O, provided with an oil-receptacle O' and channel O², by which the oil is carried directly to the end of the work being drilled, is pivoted upon the frame of the vise at L², and is so located that it may be swung

30 into or away from the path of the work in its advance through the gripping-jaws toward the spindle and latched in place at L³. An adjustable stop P is provided, by means of which the approach of the vise carrying the

35 stop-plate O toward the drilling-head may also be limited. It is clear that stop P may be so set as to permit such approach of the vise that the work abutting against its stop-plate O will come sufficiently far into the path of the

40 cutting-tool to be reamed to the desired depth without danger of being drilled or reamed beyond such desired depth; also, in special cases, if the stop-plate O be swung out of the path of the work, the work itself may be advanced through the vise far enough to receive any desired depth of reaming without

45 interference with the adjustment of the stop P, which may remain properly set for the majority of the work required. It is obvious

50 that many constructions by means of which this stop-plate O may be adjustably interposed between the work and spindle are possible within the scope of our invention thus outlined, the method shown being simply a convenient mode of its application.

In operation, the work having been gripped in the vise, as above described, and the spindles being in rotation, the swinging head is brought into the proper position by means of

60 handle C⁴, when the first cutting-tool is caused to advance by the movement of pinion G, as described. This cutting-tool having advanced to its limit, it is permitted to withdraw by the action of the spring upon its spindle, when

65 the head is moved laterally, as required, and the second spindle is caused to act in a similar manner, and so successively through the

series if more than two spindles are employed. The work may then be removed and other work inserted, when the operations are repeated.

We are aware that special combinations in machines embodying the general principles of a gripping-vise, a laterally-movable head with advancing spindles, a feeding-lever pivoted in various ways upon said laterally-moving head and which serves at the same time to move said head, and a separate lock or detent operated by said lever have been patented; but we are not aware that machines of this class have been devised embodying automatically-adjusted supporting-rests for each end of the work before gripping in the vise or embodying devices by means of which many pieces may be drilled and reamed to the same depth, or devices by means of which the laterally-movable head is firmly locked without additional pieces.

Having thus described our invention and shown wherein its features differ from those of machines most nearly approaching it in design and arrangement, we claim—

1. The combination, in a drilling-machine, of a laterally-movable head carrying two or more revolving and sliding spindles and two or more sliders having sections of gear-rack in contact with shoulders upon said spindles, and a pinion without lateral movement, but capable of rotary movement and engagement with said sections of gear-rack, the whole being so organized and arranged that the various spindles may successively receive endwise movement by the rotation of the single pinion, all substantially as described.

2. The combination, in a drilling-machine, of a laterally-movable head carrying two or more revolving and sliding spindles and provided with a series of slots arranged to temporarily hold the head in a fixed position, in combination with a segmental or mutilated pinion without lateral movement, but capable of rotary movement and engagement with said slots, all substantially as described.

3. The combination, in a drilling-machine head, of two or more spindles D, two or more sliders F, independent of said spindles, but in contact with shoulders upon said spindles, two or more spiral springs D², tending normally to prevent end motion of said spindles, and two or more pinions E, mounted within said head and around said spindles in such a manner that said spindles may receive rotary motion therefrom and at the same time be capable of endwise motion, all substantially as described.

4. The combination, in a drilling-machine, of a plate or bed-piece provided with pivot-journals B', a laterally-swinging head pivoted in said journals carrying two or more revolving and sliding spindles provided with pinions to receive rotary motion, and a pulley provided with driving-pinions or friction-disks so journaled upon one of the pivots of said swinging head as to transmit rotary mo-

tion to the spindles, all arranged and operating substantially as described.

5. The combination, in a drilling-machine, of two or more revolving and sliding spindles having collars D' with a laterally-movable head carrying said spindles and provided with two or more shoulders C⁶, to limit the advance of the sliding spindles, and two or more slots C⁸, to receive and hold sliders 10 having sections of gear-rack, substantially as described.

6. The combination, in a vise for a drilling-machine, of two opposing jaws K K', for gripping the work, and two supplemental opposing jaws K² K³, acting simultaneously with said gripping-jaws as supports for the work, substantially as described.

7. The combination, in a drilling-machine, of a vise for holding the work, movable longitudinally upon the bed of the drilling-machine and provided with a cross-bar or stop-plate O for the work, and an adjustable stop P, whereby the approach of the vise with its stop-plate O toward the head of the drilling- 25 machine may be limited, arranged and operating substantially as described.

8. The combination, in a drilling-machine of the class described, with the gripping-jaws of the vise and traversing spindle of the drilling-head, of a cross-bar, plate, or projection 30

so located and attached to the adjacent parts as to come in the path of work held in the vise and limit the approach of the work toward the drilling-head, substantially as and for the purpose described.

9. The combination, in a drilling-machine of the class specified, with the gripping-jaws of the vise and traversing spindle of the drilling-head, of a cross-bar, plate, or projection provided with an oil-receptacle and so located and pivotally attached to the adjacent parts as to be swung into the path of work held in the vise to limit its approach toward the drilling-head and at the same time supply oil to the cutting-tool, substantially as described.

10. The combination, in a center drilling-machine, of a longitudinally-movable vise consisting of opposing jaws K K', movable toward and from each other, a rest consisting of opposing jaws M M', movable toward and from each other, and means for moving all the jaws simultaneously, substantially as described.
